(57) **CLAIM**

The ornamental design for a part of a catheter manipulation device, as shown and described.

DESCRIPTION

This application is related to U.S. application Ser. No. 29/648,126, filed May 18, 2018, the entire disclosure of which is hereby incorporated herein by reference.

FIG. 1 is a perspective view of a part of a catheter manipulation device showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIGS. 8, 9, 10, and 11 are additional perspective views thereof.

In the drawings, the broken lines are for the purpose of illustrating environment only and form no part of the claimed design.

The part of a catheter manipulation device illustrated in FIGS. 1-11 may be, for example, a catheter manipulation device.

1 Claim, 9 Drawing Sheets
